RAILING UNIT

Wenzel W. Thom, 524 N. Fountain, Wichita, Kans., assignor of one-half to Cecil D. Jones, Wichita, Kans.

Filed May 21, 1962, Ser. No. 70,217

Term of patent 14 years

(Cl. D13—7)

FIG. 1 is a plan view of a railing unit, showing my new design;

FIG. 2 is a side elevational view thereof;

FIG. 3 is a side elevational view of the opposite side of the railing unit;

FIG. 4 is an elevational view with the rail fragmentarily shown;

FIG. 5 is an enlarged, horizontal, cross-sectional view of the standard portion of my railing unit, taken on the line 5—5 of FIG. 2; and

FIG. 6 is an enlarged, horizontal, cross-sectional view taken on line 6—6 of FIG. 2.

The center of the post of FIGS. 2, 3 and 4 and the rail in FIGS. 1, 2 and 3 has been broken away to indi-

cate indeterminate length. The dominant features of my design reside in the portions shown in full lines.

I claim:

The ornamental design for a railing unit, as shown and described.
